BOBBIN CLEANER

Ernest K. Bauer, Meadville, Pa., assignor to American Viscose Corporation, Philadelphia, Pa., a corporation of Delaware

Application January 20, 1954, Serial No. 405,189

7 Claims. (Cl. 28—19)

This invention relates to textile machinery and, more particularly, to mechanical apparatus for stripping waste yarn from bobbins. In prior practice, it is customary to remove waste yarn from bobbins manually; and for this purpose, the operator employs a sharp knife which scores or gouges the bobbin to such an extent that it cannot be used again without grinding or polishing. This reworking of the bobbins is sometimes more expensive than replacement. A machine which completely removes all waste yarn from the bobbin and, particularly, yarn in the corners of the bobbin without the necessity of employing sharp instruments or manual labor is very desirable from the standpoint of saving time and money. While I am aware that machines have been proposed for removing waste yarn, such devices have not been accepted by industry primarily because they have not been able to remove all the yarn effectively or because they are dangerous.

The present invention therefore has for its primary object the provision of a machine which automatically removes all the yarn from a bobbin without further manipulation once the operator has initiated the cycle.

A further object of the invention is to provide a swinging carriage for a bobbin which carries a bobbin from a loading position through a plurality of cleaning positions which successively remove yarn piled against the flange of the bobbin and, also, yarn around the main spindle of the bobbin.

A further object of the invention is to provide, in a machine of the type described, a plurality of yarn-removing brushes, at least some of which are positioned in a manner to remove yarn from the corners of the bobbin between the spindle and the flanges.

A further object of the invention is to provide, in a machine of the class described, safety devices for initiating and stopping the operating cycle.

A still further object of the invention is to provide a highly efficient waste yarn remover capable of completely removing the waste yarn from a bobbin in a matter of less than two seconds.

Further objects will be apparent from the specification and drawings in which:

Figure 1 is a top view of a waste yarn remover constructed in accordance with the present invention;

Figure 2 is a partially sectioned front view of the structure of Figure 1 as seen along the line 2—2;

Figure 3 is an end view of the structure of Figure 1 as seen at 3—3 but with the bobbin carriage in the loading position;

Figure 4 is a transverse sectional view as seen at 4—4 of Figure 2 but with the bobbin carriage in the fully advanced brushing position;

Figure 5 is an enlarged detail of the loading station as seen at 5—5 of Figure 1;

Figure 6 is an end view of the structure of Figure 5; and

Figure 7 is an enlarged sectional detail as seen at 7—7 of Figure 1;

2

Figure 8 is a view of the wiring diagram.

The invention comprises essentially the provision of a relatively wide brush. This brush is mounted in a fixed position on a framework approximately of the same width or axial length as the spindle of the bobbin to be cleaned. A pair of thin or narrow brushes are mounted at angles of approximately 30° to the horizontal in such a manner that they contact the corners formed by the bobbin spindle and the bobbin flanges. In the preferred embodiment, there are two corner brushes independently driven by separate motors and one large brush independently driven by its own motor. A bobbin carriage is pivoted on the framework so that it swings from an outer loading station past the corner brushes and thence into proximity with the wide large brush. The bobbin is caused to turn partially when in contact with the large brush, whereupon the carriage reverses to replace the bobbin at the loading station where it is quickly exchanged by the operator for the next bobbin having yarn to be removed. The entire cleaning cycle is performed in less than two seconds.

Referring now more particularly to Figures 1—3 of the drawings, the preferred embodiment illustrated therein comprises a frame assembly having a base 10 and a plurality of upright posts or pillars 11, 12, 13, 14, 15 and braces 16, 16. The main cleaning brush 20 is secured to a horizontal shaft 21 by means of flanges 22, 22 and nut 23. Shaft 21 is journaled in bearings 24, 24 and driven from an independent motor 25 through pulleys 26, 27 and belt 28. The small corner brushes 30 and 30' are identical to each other and mounted on the armature shafts 31 and 31' of motors 32 and 32'. Motors 32 and 32' are supported on posts 12 and 13 respectively by angle brackets 33 and 33' so that the centerlines of shafts 31 and 31' are approximately 30° from the horizontal. The horizontal spacing of the motors will, of course, be determined by the length of the particular bobbins B which are being cleaned. Suitable adjustment for bobbin length, brush diameter and wear is provided by means of slotted mountings for the motors, the brackets, and the bearings 24 for brush 20.

The bobbin B is securely clamped between the centers of a pivoting carriage journaled at 35 and 36 on posts 12 and 13. A shaft 37 supports the carriage and has spaced housings 38 and 39 connected to the shaft through links 40, 40. Oscillation of the carriage about the center of shaft 37 is controlled through rocker arms 41 and 42 keyed to each end of the shaft. The main driveshaft 45 is journaled at each end in bearings 46, 46 on pedestals 11 and 14. The shaft 45 is provided with a combined flywheel and cam at each end thereof, the cam 47 being keyed to the left end of the shaft and the cam 48 being keyed to the right end thereof. The inner face of each cam or fly wheel 47 and 48 is provided with an axially facing cam track 49 which is allochiral on each cam. These cam tracks control the oscillation of shaft 37 through cam followers 50, 50 on the rocker arms 41 and 42. Figures 3 and 4 illustrate the extreme positions of this pivoting oscillatory movement. In Figure 3 the carriage is in its outermost or loading position, whereas in Figure 4 the carriage is in its innermost position in which the bobbin contacts the large brush 20. Since the cycle of cleaning a bobbin is completed in one revolution of the main driveshaft 45, I provide a cycling control switch 55 associated with cam 47 and controlled by a rise 56 on the periphery of the cam. When in the loading or unloading position of Figure 3, the circuit to the main motor 57 is held open by switch 55; but once the cycle is initiated, the switch remains closed for a complete revolution of the shaft 45 until it is again opened by the rise 56.

The left face of each cam 47 and 48 controls the bob-

bin clamping mechanism which is mounted in the housings 38 and 39. The bobbin is inserted or removed between housings 38 when the carriage is in its outermost position shown in Figure 3. The operator displaces a spring-loaded collar 60 on bobbin shaft 61 to permit insertion of the bobbin between shaft 61 and its opposite aligned shaft 62. Both of the shafts, however, are movable axially and controlled by helical compression springs 63 and 64 to insure that the bobbin B is engaged between centers during the yarn removal process. This is accomplished by means of the rocker arms 65 and 66 pivoted in bifurcated brackets 67 and 68 respectively. The lower end of arm 66 is provided with a roller 69 which engages the outer face of cam 47. This outer face, however, has a depression or indentation 70 which is in line with roller 69 when the carriage is in its loading position shown in Figure 3. The shaft 61 is thus urged outwardly under pressure of spring 63 so that the bobbin center on the end of shaft 61 is moved away from shaft 62 sufficiently far to permit the bobbin to be loaded by the operator. Similar control of shaft 62 is provided through rocker arm 65 which is actuated by the inner face of cam 48 through roller 71. A rise 72 on the inner face of cam 48 pivots rocker arm 65 clockwise when the driveshaft 45 moves the carriage to the unloading position of Figure 3. This in turn compresses spring 64 and slides shaft 62 axially to the right. Thus, both bobbin shafts 61 and 62 are moved in opposite directions to permit loading and unloading of the bobbin; but once the carriage has been moved to the unloading position between the shaft centers by spring 64, thus insuring that it cannot be withdrawn from the carriage until the cycle is completed.

Shafts 61 and 62 are provided from both ends of the carriage with a pair of brake shoes 73 and 74 which are urged against the pulley 77 keyed to shaft 61. However, to remove all of the yarn from the center of the bobbin, it is desirable to rotate the bobbin through a partial revolution

when it is in contact with the large brush 20. For this purpose, I mount a motor 80 on framework post 15 which turns a flat pulley 81 through a reduction gear drive 83. Pulley 81 has a facing 82 and registers with pulley 77, the diameters of the pulleys and the location of pulley shaft 84 being such that the pulleys contact each other momentarily as the bobbin carriage swings to its maximum inward pivoted position. At this point the brake 75 is released by a rocker arm 85 that contacts an adjustable stop or abutment 86. This in turn pivots the brake shoe on pin 87 through a lever 88 integral with the shoe and a connecting link 89. As soon as the carriage swings forward again, a compression spring 90 clamps the brake against pulley 77 to prevent further rotation of the shaft and bobbin.

In a somewhat similar manner, the main shaft 45 is prevented from turning or spinning after the circuit is broken to the main motor 57 to insure that the carriage always stops in the proper forward loading position and the switch actuator 56 always holds switch 55 open as shown in Figure 3. Shaft 45 is driven through a pair of meshing spur gears 91 and 91a which in turn are driven by motor 57, shaft 93 and reduction until 94. Shaft 93 is provided with a brake drum 95 (Figure 7) which cooperates with a pair of brake shoes 96 and 97 actuated by means of a solenoid 98 and connecting linkage 99, 100, 101, and 102. The brake shoes are pivoted at 103 and 104 and compressed against the brake drum 95 by means of a spring 105 which actuates the shoes through rod 106. When the circuit is closed to the main motor 57, solenoid 98 is energized, thus pivoting lever 100 counterclockwise and spreading the upper ends of the brake shoes. As soon as switch 55 is opened, the solenoid is de-energized, locking both shafts 93 and 45, thus insuring instantaneous stopping of the mechanism.

In operation, the bobbin B to be stripped is placed in

a pair of saddles 110 and 111 (Figures 5 and 6) which position the bobbin in line with the shafts 61 and 62. For this purpose the collar 60 is readily displaced by compressing spring 112 (Figure 2). When the bobbin is in the proper aligned position with shafts 61 and 62, the flanges 113 and 114 of the bobbin close micro-switches 115 and 116 respectively through plungers 117 and 118. The operator then removes his hand from the bobbin and depresses starting handle 119 which closes micro-switch 120. The handle 119 is pivoted in frame members 121 and 122 and has an upper limit stop 123 and an adjustable lower limit stop 124. Micro-switches 115, 116 and 120 are all connected in series with each other across the terminals of switch 55 so that only when the three switches, 115, 116 and 120, are closed will motor 57 start. However, as soon as the motor does start, rotation of cam 47 closes switch 55 whereupon the operator removes his hand from handle 119, thus opening switch 120 when the handle pivots upwardly under tension of spring 125. As soon as cam 47 completes one revolution so that the rise 56 opens switch 55, the circuit to motor 57 is opened and brake shoes 96 and 97 are applied. Bobbin B is then removed and exchanged for the next bobbin to be stripped and the cycle is repeated.

Ordinarily, I provide a suitable hood and vacuum induced draft in the hood to remove waste yarn from all three of the brushes. For the purpose of clarity, the hood and its associated vacuum pump are not shown in the drawings.

It will thus be understood that I have provided an apparatus which will strip the waste yarn from bobbins which will not damage the bobbin and which is capable of the described my invention. I claim:

1. An apparatus for stripping waste yarn from bobbins, which will not damage the bobbin and which is capable of the described my invention. I claim:

2. An apparatus in accordance with claim 1 in which the carriage is oscillated by means of two cams keyed to a main drive-shaft.

3. An apparatus in accordance with claim 1 in which the carriage is provided with a pair of bobbin centers

55 axially movable in the carriage, and cam means for opening said centers to receive a bobbin and thence close

the centers to securely clamp the bobbin therebetween

during the stripping operation.

4. An apparatus in accordance with claim 1 having means

60 for turning the bobbin on its axis when the bobbin is being stripped by the main brush.

5. In mechanism for stripping waste yarn from bobbins

and the like, a framework, a main stripping brush mounted

65 in said framework, means for turning said main brush,

65 a pair of corner stripping brushes mounted on said frame-

work at an angle to the centerline of the bobbin to be

stripped, means for turning each of said corner stripping

brushes, a carriage swingable from a loading position

to a stripping position in contact with said brushes, a

motor for oscillating said carriage, a loading station for

45 the brushes in line with the outwardly oscillated position

of the carriage, and electrical switches at the loading sta-

70 tion for closing the circuit to said motor when a bobbin

is properly positioned on the loading station and a start-

ing handle is depressed.

60 2. Apparatus in accordance with claim 1 in which the

carriage is oscillated by means of two cams keyed to a

main drive-shaft.

65 3. Apparatus in accordance with claim 1 in which the

carriage is provided with a pair of bobbin centers

55 axially movable in the carriage, and cam means for opening

60 said centers to receive a bobbin and thence close

the centers to securely clamp the bobbin therebetween

65 during the stripping operation.

70 4. Apparatus in accordance with claim 1 having means

65 for turning the bobbin on its axis when the bobbin is being

stripped by the main brush.

75 5. In mechanism for stripping waste yarn from bobbins

and the like, a framework, a main stripping brush mounted

60 in said framework, means for turning said main brush,

65 a pair of corner stripping brushes mounted on said frame-

work at an angle to the centerline of the bobbin to be

stripped, means for turning each of said corner stripping

brushes, a carriage swingable from a loading position

to a stripping position in contact with said brushes, a

motor for oscillating said carriage, driving connections

70 between said motor and the carriage, a brake associated

with said driving connections, means for applying said

brake when the carriage is in an outwardly oscillated

position, a loading station for the brushes in line with

75 the outwardly oscillated position of the carriage, and

electrical switches at the loading station for closing the circuit to said motor when a bobbin is properly positioned on the loading station and a starting handle is depressed.

6. In mechanism for stripping waste yarn from bobbins and the like, a framework, a main stripping brush mounted in said framework, means for turning said main brush, a pair of corner stripping brushes mounted on said framework at an angle to the centerline of the bobbin to be stripped, means for turning each of said corner stripping brushes, a carriage swingable from a loading position to a stripping position in contact with said brushes, a motor for oscillating said carriage, a loading station for the brushes in line with the outwardly oscillated position of the carriage, and means for initiating said stripping cycle when the carriage is at said outwardly oscillated position.

7. In mechanism for stripping waste yarn from bob-

bins and the like, a framework, a main stripping brush mounted in said framework, means for turning said main brush, a pair of corner stripping brushes mounted on said framework at an angle to the centerline of the bobbin to be stripped, means for turning each of said corner stripping brushes, a carriage swingable from a loading position to a stripping position in contact with said brushes, a motor for oscillating said carriage, a loading station for the brushes in line with the outwardly oscillated position of the carriage, means for turning the bobbin in the carriage when the bobbin is in contact with the main stripping brush, and electrical switches at the loading station for closing the circuit to said motor when a bobbin is properly positioned on the loading station and a starting handle is depressed.
